UNITED STATES PATENT OFFICE.

GEORGE SYLVESTER TIFFANY, OF TECUMSEH, MICHIGAN.

CRUSHER FOR CLAY, CLODS, &c.

SPECIFICATION forming part of Letters Patent No. 307,820, dated November 11, 1884.

Application filed May 19, 1884. (No model.)

To all whom it may concern:

Be it known that I, GEORGE S. TIFFANY, a citizen of the United States of America, residing at Tecumseh, in the county of Lenawee 5 and State of Michigan, have invented a certain new and useful Improvement in Crushers, of which the following is a specification.

My invention relates to improvements in machines for crushing material preparatory to 10 submitting the material to further disintegration, and has special relation to the preparation of clay, clods, &c., for the action of the grinding or pulverizing machinery.

The object of my invention is to provide a 15 machine to take and crush hard and unyielding clods of clay and such foreign substances as may be mixed with it into such comminuted state that it may be readily, freely, and altogether taken in by the grinding or pulverizing 20 machinery.

My invention therefore consists in the novel construction and combination of parts, as will be hereinafter more fully described, and specifically stated.

25 In the accompanying drawings, fully illustrating my improved machine and forming a part of this specification, Figure 1 is a perspective of the complete machine. Fig. 2 is a plan view thereof. Fig. 3 is a vertical sectional view taken through the line $x-x$ of Fig. 2, and Fig. 4 is a detail view of one of the crusher bars or blades, with a transverse sectional view showing the shape of the blades in cross-section.

35 The letter A represents the frame of the machine, made up of the side pieces, a a' , cast solid with the top and bottom cross-pieces, b b' , intermediate cross-pieces, c c' , and vertical standards d d' , formed with journal-bearings 40 e . These side pieces of the frame are secured together at the top at each end by strong tie-plates f , substantially as shown, and the frame of the machine is further formed or provided with journal-bearings g for the crank-shaft, 45 and h for the stationary crushers, and i for the driving-shaft.

The letter B represents the driving-shaft, journaled in or to the hind standards of the frame in bearings i . This shaft is provided 50 with a belt-pulley on one end, and on the other end is fixed the gear-wheel k , the latter of which meshes with the larger gear-wheel, C ,

on the shaft D, working in bearings g on the frame. This shaft D has fixed to it the crank-arm l , the free end of which has attached 55 thereto one end of the connecting-rod m . The other end of said rod is fitted to the shaft E, and to the arm of the gear-wheel C is fixed a wrist-pin, l' , arranged coincident with the crank-arm l , and attached to this wrist-pin l' 60 is the connecting-rod m' , the other end of which is connected to the shaft E, substantially as shown in Fig. 2 of the drawings.

It is apparent that instead of attaching the connecting-rod m' to a pin on the gear-wheel 65 C, the shaft D may be extended and a duplicate crank-arm be fixed thereto, to which the connecting-rod can be attached.

The letters F and F' represent a number of 70 blades or bars, the lower ends of which are arranged in alternate succession on the shaft n , resting in fixed bearings e in the vertical standards of the frame. The upper ends of 75 the bars F are arranged on the shaft q , held in bearings h on the frame, and secured in place by any proper means. These bars or blades F are set to incline from their base rearward 80 to their top. The bars or blades F' have their upper ends arranged on the shaft E, which is connected to the crank-arms by the connecting-bars m and m' , substantially as shown.

In Fig. 4 is shown the particular form of 85 one of the blades in full, and also the shape in cross-section, the latter showing the form as taken through the line $y-y$ of the remaining detail of the figure. It will be seen that the 90 face or operating-edge 1 is square, and that the blade extends of uniform thickness for a short distance rearward of the face and then is made somewhat wedge shaped. This particular construction gives sufficiently broad contacting-face surface for all purposes and widens the distances between the backs of the blades, so that the material forced through the interstices shall not stick between the 95 blades and clog the machine. The lower ends of the blades are formed with solid circular disks 2, and the perpendicularity of each blade is maintained by forming the upper ends with a solid collar, 3, on each side.

Secured to each side of the frame, and arranged to cover the space between the center blades, are triangular-shaped plates G' . These serve to prevent the material submitted to

the machine from dropping out or from being forced out at the sides of the grates or basket. The bars or blades may be secured against lateral displacement by arranging on the respective shafts sleeves or washers with set-screws to set them in any desired position. In arranging the bars it is intended that the crank-connection shall move the reciprocating blades so that their faces for the whole length shall operate as crushing-surfaces, and so that by passing into the interstices of the stationary bars they shall serve to push out and free the material from between both series.

15 The operation is as follows: The power being applied to the driving-shaft, motion is communicated to the large gear-wheel, which turns the cranks and gives a reciprocating motion through the connecting-rods to the outer set of bars, which in their inward movement press the material in the machine against the stationary bars and effect the disintegration of whatever may oppose the pressure.

What I claim, and desire to secure by Letters Patent, is—

20 1. A blade or bar for a crusher formed with a flat contacting face and wedge-shaped body in cross-section, and provided with apertures in each end to receive sustaining-shafts, substantially as described.

25 2. The stationary bars or blades having their upper and lower ends arranged on fixed shafts, in combination with the movable bars or blades having their lower ends arranged on a fixed shaft and interposed in alternate succession between the stationary bars or blades on the same fixed shaft, and their upper ends arranged on a movable shaft connected to means for reciprocating it, substantially as described.

30 3. A series of fixed bars or blades having their upper ends arranged on a fixed shaft, and a series of movable bars or blades having

their upper ends arranged on a movable shaft, and both series having their lower ends arranged on the same fixed shaft in alternate succession, in combination with the side plates arranged and secured to cover the space between the outer blades, substantially as described.

4. A series of fixed bars or blades having their upper ends arranged on a fixed shaft, and a series of movable bars or blades having their upper ends arranged on a movable shaft, and both series having their lower ends arranged on the same fixed shaft in alternate succession, in combination with the crank-rods, the shaft having a gear-wheel fixed thereon, and provided with means, substantially as described, for reciprocating the crank-rods and driving-shaft, with gear-wheel meshing with the gear-wheel on the crank-shaft, substantially as described.

5. A series of fixed bars or blades having their upper ends arranged on a fixed shaft, and a series of movable bars or blades having their upper ends arranged on a movable shaft, and both series having their lower ends arranged on the same fixed shaft in alternate succession, in combination with the frame provided with side plates arranged to cover the space between the outer opposite blades, the crank-rods, shaft having a gear-wheel mounted therein, and provided with means, substantially as described, for reciprocating the crank-rods and driving-shaft, with gear-wheel meshing with the gear-wheel on the crank-shaft, substantially as described.

In testimony whereof I have hereunto set my hand in the presence of two attesting witnesses.

GEO. SYLVESTER TIFFANY.
